United States Patent Office.

D. C. SAGE, OF MIDDLETOWN, CONNECTICUT.

Letters Patent No. 70,748, dated November 12, 1867.

IMPROVED CONSTRUCTION OF BUTT-HINGES.

The Schedule referred to in these Letters Patent and making part of the same.

TO ALL WHOM IT MAY CONCERN:

Be it known that I, D. C. SAGE, of Middletown, in the county of Middlesex, and State of Connecticut, have invented a new and improved Hinge; and I do hereby declare that the following is a full, clear, and exact description thereof, reference being had to the accompanying drawings, making a part of this specification, in which—

Figure 1 is a face view of the improved hinge.

Figure 2 is an inside view of the same with removable plates attached.

Figure 3 is a sectional view taken in the plane indicated by red line $z z$ in fig. 2.

Figure 4 is an end view of fig. 2.

Figure 5 is a sectional view through the eye of a hinge, showing washers applied to it.

Figure 6 is a horizontal sectional view of the hinge of fig. 5.

Similar letters of reference indicate corresponding parts in the several figures.

The first part of my invention provides for securing a butt hinge to a door-casing, and also to the door thereof, in such manner as not to expose the heads of the retaining-screws, by means of plates which are secured to the casing and door, and which are adapted for receiving hooks that are cast on the back faces of the leaves of the hinge, as will be hereinafter described.

The second part of my invention consists in the application of hardened-metal washers between the eyes of the hinge, in such manner as to prevent the hinge from readily wearing at such points, as will be hereinafter described.

To enable others skilled in the art to understand my invention, I will describe its construction and operation.

The hinges which I have represented in the drawings may be made of the well-known shape of door or shutter butt-hinges, and of any suitable size.

The first part of the invention is more particularly applicable to ornamental door-hinges, where it is desired to have them present a handsome appearance when on the door. Instead of casting the leaves of the hinges with holes through them, as shown in fig. 5, I cast a suitable number of hooked projections, $a a$, upon the back surfaces of each leaf A. The hooks on one leaf are directed upward, and those on the opposite leaf are directed downward, as shown in fig. 2. The projections $a a$ may be made of the rectangular form shown, or of any other form which will afford the greatest strength and convenience of attachment. In conjunction with a hinge thus constructed, I use plates of steel or wrought metal, as shown at B B, which may be made quite thin, and which may be equal to or a little less in length than the length of the leaves of the hinge. By means of suitable dies, I form rectangular holes through these plates B B, slightly larger than the hooks $a a$, but corresponding in arrangement and distance apart to these hooks. At intermediate points between the holes through plates B, for receiving the hooks a , I make countersunk holes for receiving the screws, by which these plates are rigidly secured to the door and door-casing previously to "hanging" the door. The plates having been secured to the door and its casing, it will be a very simple operation to hook on the hinges and "hang" the door.

The second part of my invention consists in casting the hinges with circular recesses in the ends of their eyes $c c$, as shown in figs. 5 and 6, into which are fitted perforated steel or other hardened-metal disks, $d d$, which afford abutments or bearings for the adjacent eyes of the hinge, and prevent these abutting surfaces from readily wearing out and allowing the door to sag and the hinge to work loose.

Having described my invention, what I claim as new, and desire to secure by Letters Patent, is—

1. The attachment of butt-hinges to door-casings and doors, by means of hooks and plates, substantially as described.
2. The construction of the leaves of hinges with hooks $a a$, or their equivalents, upon them, for being received by perforated plates B, substantially as described.
3. The washers $d d$, of hardened metal, and detached from the pintle of the hinge, applied in recesses at the joints of the hinge, substantially in the manner and for the purpose described.

D. C. SAGE.
